METHOD OF MAKING FRENCH SEAMS

Filed Dec. 22, 1930

UNITED STATES PATENT OFFICE

HORACE F. GRUMAN, OF ST. LOUIS, MISSOURI, ASSIGNOR TO LEWIS INVISIBLE STITCH MACHINE COMPANY, OF ST. LOUIS, MISSOURI, A CORPORATION OF MAINE

METHOD OF MAKING FRENCH SEAMS

Application filed December 22, 1930. Serial No. 504,197.

This invention relates to new and useful improvements in methods of forming French seams.

Heretofore, a French seam has been formed by first superposing two body fabrics with two of their edges in register, then joining the superposed fabrics by a line of stitches disposed in parallelism to the edges of the fabrics, then folding both body fabrics over the joining seam, and finally seaming the fabrics with a line of stitches extending parallel to the first line of stitches. This method is obviously slow and consequently rapid production cannot be obtained. Furthermore, this method has often resulted in the marginal edge portions of the fabrics being projected through the second seam and consequently a ragged and unsightly French seam has been thereby produced.

Among the several objects of my invention are to provide a method of forming French seams wherein rapid production can be obtained, and to provide such a method whereby the marginal edge portions will be completely hidden from view and a French seam of the highest quality will be produced.

In the accompanying drawing:—

Figure 1 is a perspective view showing generally the successive steps employed in my invention,

Figure 2 is a sectional view showing more or less diagrammatically the second step in my method,

Figure 3 is a sectional view showing more or less diagrammatically the third step in my method,

Figure 4 is a sectional view showing more or less diagrammatically the fourth step in my method,

Figure 5 is a sectional view showing more or less diagrammatically the fifth step in my method, and

Figure 6 is a perspective view of a French seam.

Different specific mechanisms for carrying out the steps of my improved method are disclosed in my co-pending applications Serial No. 238,793, filed Dec. 9, 1927, and Serial No. 274,884, filed May 3, 1928.

In the present invention, I first take two

body fabrics A and B and turn the adjacent marginal portions *a* and *b* out of the general plane of the fabrics into side-by-side relation, these portions *a* and *b* being preferably turned downwardly as shown in Figure 1. 55 These vertical marginal portions while in this relation are then joined by a line of through stitches *c* as shown in Figure 2. I have thus formed what will be hereinafter referred to as the initial or first seam. I then trim the marginal portions *a* and *b* below and close to the stitches *c* by a trimming means as shown in Figure 3. I then form an upwardly extending ridge *d* in the seamed and trimmed body fabrics by a suitable means, as 60 shown in Figure 4. This ridge *d* extends along the line of the initial seam and includes the latter, the upwardly extending inside marginal portions *e* and *f* of the body fabrics being disposed in side-by-side relation and 65 entirely covering or embracing the line of stitches *c* and the trimmed marginal portions *a* and *b*. By the term "inside" I refer to those marginal portions of the fabrics which are inside of the line of stitches *c*, as distinguished from those marginal portions which are outside of the line of stitches *c* and which have been trimmed. I then join the upturned inside marginal portions *e* and *f* by a 70 line of stitches *g* as shown in Figure 5, and 75 thereby form the second or final seam, the line of stitches *g* extending in parallelism with the initial seam but spaced slightly below the trimmed edges thereof. Thus by trimming the marginal portions *a* and *b* of 80 the initial seam, I am enabled to form the stitches *g* close to the stitches *c* but without showing any of the marginal portions *a* and *b* in the finished seam.

Although, I have shown and described the 85 edge portions *a* and *b* as being turned downwardly and the ridge *d* projected upwardly, it will be understood that my invention embraces the idea of the edge portions *a* and *b* being turned upwardly and the ridge *d* being 90 projected downwardly.

I claim:—

1. The method of French seaming body fabrics, consisting in turning the adjacent marginal portions out of the general plane of 100

said fabrics, then seaming said marginal portions while thus turned by a line of stitches, then forming a ridge in the seamed fabrics along the line of and including the seam and
5 with the marginal portions of the seam disposed within the ridge, and then seaming the ridged portion of the fabrics by a line of stitches in spaced relation to the line of stitches of the first seam while the fabrics re-
10 main in the same general plane.

2. The method of French seaming body fabrics, consisting in turning the adjacent marginal portions out of the general plane of said fabrics, seaming said marginal portions
15 while thus turned by a line of stitches, then trimming the turned marginal portions beyond the line of stitches, then forming a ridge in the seamed fabrics along the line of and including the seam and with the marginal portions of the seam disposed within the ridge, and then seaming the ridged portion of the fabrics by a line of stitches in spaced relation to the trimmed edges of the first seam while the fabrics remain in the
25 same general plane.

3. The method of French seaming body fabrics, consisting in turning downwardly the adjacent marginal portions of two body fabrics, then seaming the downwardly turned marginal portions by a line of stitches, then forming an upwardly extending ridge in the seamed fabrics along the line of and including the seam and with the marginal portions of the seam disposed within the ridge,
30 and then seaming the ridged portion of the fabrics by a line of stitches below the first seam while the fabrics remain in the same general plane.

4. The method of French seaming body fabrics, consisting in turning downwardly the adjacent marginal portions of two body fabrics, then seaming the downwardly turned marginal portions by a line of stitches, then trimming the downwardly turned marginal portions below the line of stitches, then forming an upwardly extending ridge in the seamed fabrics along the line of and including the seam and with the marginal portions of the seam disposed within the
45 ridge, and then seaming the ridged portion of the fabrics by a line of stitches below the trimmed edges of the first seam while the fabrics remain in the same general plane.

In testimony whereof I affix my signature.

55 HORACE F. GRUMAN.
